FOLDING SCREEN

William J. Schickel, O'Bannoville Road, Loveland, Ohio 45140, and Armand Re, Loveland, Ohio; said Re assignor to Schickel

Filed May 17, 1968, Ser. No. 11,987

Term of patent 14 years

Int. Cl. D6—01

U.S. Cl. D33—1

FIG. 1

FIG. 2

FIGURE 1 is a perspective view showing one side of a folding screen embodying the invention, both sides of the folding screen being alike.

FIGURE 2 is an enlarged fragmentary perspective view of one of the screen panels illustrating details of the design.

The design is characterized by a series of screen forming panels hingedly connected together to form a folding screen, each of the screen panels being characterized by a spaced apart pair of vertically disposed frame members having flat caps at their opposite ends, the vertical frame members being interconnected by a pair of horizontally disposed frame members spaced inwardly from the ends of the vertical frame members, the frame members each being square in cross-section and of the same cross-sectional dimensions, the space enclosed by said vertical and horizontal frame members being spanned by a flexible sheet material having pockets at its opposite ends which surround and cover said horizontal frame members.

We claim:

The ornamental design for a folding screen, as shown and described.
